Attn:

UNITED STATES PATENT OFFICE.

WILLIAM C. PEET, OF NEW YORK, N. Y., ASSIGNOR TO THE J. L. MOTT IRON WORKS, OF SAME PLACE.

DESIGN FOR A SUPPORTING-LEG.

SPECIFICATION forming part of Design No. 31,893, dated November 28, 1899.

Application filed November 3, 1899. Serial No. 735,720. Term of patent 7 years.

To all whom it may concern:

Be it known that I, WILLIAM C. PEET, a citizen of the United States, residing in the city, county, and State of New York, have invented and produced a new and original Design for a Supporting-Leg, of which the following is a specification.

This design is shown in the accompanying drawing.

The leg is especially intended for supporting a washbasin or lavatory and is usually of porcelain.

The leading feature of this design for a leg

consists in the nearly globular upper part *a*, with the circular ribs or beads at *b c* above and below the globular part, and the tapering portion *d*, terminating with a bulb *e* at the lower end.

I claim—

The design for a supporting-leg substantially as described and shown.

Signed by me this 25th day of October, 1899.

WILLIAM C. PEET.
